[57] CLAIM

The ornamental design for a pipe clamp for a round pipe, as shown and described.

DESCRIPTION

FIG. 1 is a front, right side perspective view of a pipe clamp for a round pipe of the subject design, the broken line showing of portions of a pipe being for illustrative purposes only;

FIG. 2 is a top plan view of the subject design, the bottom being a mirror image;

FIG. 3 is a front elevational view of the subject design;

FIG. 4 is a rear elevational view of the subject design;

FIG. 5 is a right side elevational view of the subject design; and,

FIG. 6 is a left side elevational view of the subject design.

FIG. 1

FIG. 2

FIG. 3

FIG. 4

FIG. 5

FIG. 6
